(57) **CLAIM**

The ornamental design for a jet face, as shown and described.

DESCRIPTION

FIG. 1 is a perspective drawing of the jet face design of the invention;

FIG. 2 is a front view of the jet face illustrated in FIG. 1; and,

FIG. 3 is a side view of the jet face illustrated in FIG. 1.

The broken line showing of parts of the drawings is included for the purpose of illustrating use and environment and forms no part of the claimed design.

1 Claim, 2 Drawing Sheets

FIG. 2

FIG. 3
